(54) **WATER WHEEL**

(76) Inventor: **Abraham Straub**

Abraham & Straub, Milton, Northumberland, Pa. Inv.
Letters Patent,

The Schedule referred to in these Letters Patent and making part
of the same containing a description in the words of the said Abraham
Straub himself of his improvement for the construction
of the Reaction Water-wheel.

It will be when this presents shall come to
Be it known that A. Abraham & Straub of the Borough of Milton,
and County of Northumberland and State of Pennsylvania, have
invented a new and useful improvement in the construction of the
"Reaction Water" wheel which has not been heretofore used or known.
the nature of which is such as to present an involute shaped
bucket or float, to the action of the head of water, under such
an improved mode of constructing this involute, as that its dis-
tance from its centre shall increase, regularly and continually,
thereby affording an uninterrupted discharge of the water with
but little resistance being afforded from the imperfection of that
found in those methods heretofore used always provided that
there shall be two or more ports of discharge for the water, or
collects, placed at regular distances for the purpose of affording
the requisite balance in the motion of the wheel. The space the
said involute is to occupy must be placed as near to the circum-
ference of the circular case of the wheel as practicable and
the manner and the principle of constructing this involute
is set forth in the following description. Having determined the
required circumference of the circular case or wheel, proceed to cut
in front towards the center a space as may be desired, for the gradual
unfolding of the involute from its commencement till termination
a collect. Then let the center on which it is to be formed, be of such
circumference as to equal that portion of the radius cut off
by this said space and pass around it without being long enough
thus completing this said circumference, to extend to the spot near
the center, from whence the involute will commence and continue.

described the inside curve (when the float is to be carried all the way round) and the distance it drops from the point of start at this end will be the outlet for the water, including the thickness of the involutes. This is in order to get that one for the outside, reduced the size of the centre so much as that the same when when applied around it shall pass the first described curve a distance equal to the thickness desired for the involutes, commencement from which point the progress of the end of the thread when unrolled will be found to describe another, or gradually approaching the first described one so as to form the thickness of the involutes float, upon a regular taper, i. outlet or point of discharge. This same process is used for forming smaller involutes when two or more are to be used, always bearing in mind the necessary increase of circumference to be given to the centre according to the number of said involutes required - as two involutes will require the centre to be twice the diameter, that is, a wheel for only half the distance, is to be gone over at the circumference of the case & yet the drop or width of outlet must be the same for these involutes - it will require a centre of three times the circumference &c. It will also be evident that the diameter of the wheel, the number of the floats, and the quantity of water to be discharged, is always to be in proportion to the height of the head of water, and to the power required. The first described curve with its commencement be continued a little beyond the line of the rim of the wheel, wherein I have described both the curves, terminate so that they shall there allow said edge to be formed by another curve, brought from the commencement of the second described and, and diminishing the thickness of the involutes to said edge, so as to afford every facility for the water to pass.

What I claim as my invention and for which I now ask Letters Patent is, the manner of forming the above described involuted float, according to the principles of construction above set forth & explained. In testimony that the aforesaid

is a full description of my improvement. I have herewith set
my hand
